STEAM CABINET

Robert G. Plantholt, 1184 W. Tienken Road,
Rochester, Mich.

Filed Feb. 15, 1965, Ser. No. 83,819

Term of patent 14 years

(Cl. D83—1)

FIG. 1

FIG. 2

FIG. 3

FIG. 4

FIG. 5

FIGURE 1 is a front elevational view of a steam cabinet showing my new design.

FIGURE 2 is a side elevation thereof.

FIGURE 3 is a top view thereof.

FIGURE 4 is a side elevation thereof as seen from the side opposite to that shown in FIGURE 2.

FIGURE 5 is a rear elevation thereof.

I claim:

The ornamental design for a steam cabinet, substantially as shown.
